UNITED STATES PATENT OFFICE.

LOUIS F. HESS, OF ANSTED, WEST VIRGINIA.

MINING-MACHINE.

1,147,724.

Specification of Letters Patent.

Patented July 27, 1915.

Application filed November 21, 1914. Serial No. 873,313.

To all whom it may concern:

Be it known that I, LOUIS F. HESS, a citizen of the United States, residing at Ansted, in the county of Fayette and State of West Virginia, have invented a new and useful Mining-Machine, of which the following is a specification.

The device forming the subject matter of this application is a mining machine of 10 that general type in which the cutter shaft rotates and slides longitudinally as it rotates.

One object of the present invention is to provide novel mechanism for rotating the cutter shaft and for imparting a longitudinal sliding movement thereto.

A further object of the invention is to provide novel means for coupling up with the driving mechanism, the drums controlling the flexible elements whereby the position of the machine is adjusted with respect to the work.

It is within the scope of the invention to improve in particulars which will be pointed out hereinafter, the construction of a mining machine of the general type disclosed in this application.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawing:—Figure 40 1 shows the invention in top plan, portions of the casing being removed; Fig. 2 is a vertical longitudinal section taken along a median plane; Fig. 3 is a horizontal section taken along the line 3—3 of Fig. 2; Fig. 4 is a vertical longitudinal section taken along the line 4—4 of Fig. 1; Fig. 5 is a cross section taken along the line 5—5 of Fig. 3; Fig. 6 is a transverse section of one of the drums; Fig. 7 is a transverse section taken approximately along the line 7—7 of Fig. 1, parts being omitted; Fig. 8 is a side elevation of one of the gear wheels depicted in Fig. 7, the shaft of the gear wheel appearing in section; and Fig. 9 is an elevation of 55 the gear wheel shown in Fig. 8, one of the side disks of the gear wheel being removed.

In carrying out the present invention

there is provided a supporting structure embodying a base plate 1 and a casing 2, the latter including a top 3, terminated intermediate the front and rear of the machine, the rear end of the casing 2 being shown at 4.

Fixed to and upstanding from the base 1 and preferably formed integrally therewith is a rear bearing 5.

Located in front of the rear bearing 5 is a transverse intermediate bearing 6.

Located in front of the intermediate bearing 6 is an intermediate partition 7 formed integrally with a longitudinal bearing 8 which is connected with the base plate 1, the longitudinal bearing 8 terminating in a front plate 9 abutting against the front wall of the casing 2. As shown best in Fig. 75 3, the intermediate bearing 6 is connected with the transverse partition 7 by means of side walls 10 which are connected with the base plate 1. As Fig. 2 will most clearly show, when compared with Fig. 1, transversely spaced upper bearings 11 are secured to or formed integrally with the longitudinal bearing 8.

A motor 12 which preferably is driven electrically, is united with the rear end 4 of the casing 2 and is supported upon the intermediate bearing 6, as shown in Fig. 2.

The armature shaft of the motor 12 is denoted by the numeral 14 and carries a pinion 15 meshing into a gear wheel 16, the tubular 90 hub 17 of which is mounted to rotate in the rear bearing 5.

Located in front of the gear wheel 16 is a pinion 18, the tubular hub 19 of which passes rearwardly through the tubular hub 95 17 of the gear wheel 16.

Mounted to rotate in the hub 19 of the pinion 18 and to slide longitudinally therein is a cutter shaft 20 provided with a keyway 21 co-operating with a keyway 22 in the hub 19 100 of the pinion 18. The keyways 21 and 22 may receive key balls 23 or their mechanical equivalents, the construction being such that although the cutter shaft 20 is connected to the pinion 18 for simultaneous rotation 105 therewith, the shaft nevertheless may slide longitudinally in the pinion. The rear end of the hub 17 of the gear wheel 16 and the rear end of the hub 19 of the pinion 18 are provided with clutch elements 24 adapted to 110 be engaged by a clutch 25 slidable upon the shaft 20 longitudinally of the shaft.

Disposed upon opposite sides of the cutter shaft 20 are longitudinal shafts 26 jour-

naled for rotation in the intermediate partition 7 and in the intermediate bearing 6.

To the rear ends of the longitudinal shafts 26 are secured pinions 27 which mesh into the pinion 18.

The forward ends of the longitudinal shafts 26 are equipped with worms 28 co-operating with worm wheels 29 fixed to a shaft 30 journaled in the lower rear portions 10 of the upper bearings 11. The worm wheels 29 are provided with wrist pins 32 receiving the forward ends of pitmans 31, the rear ends of which are pivoted on studs 33 at the ends of a cross head 34 in which 15 cutter shaft 20 is journaled.

Attached to the cutter shaft 20 in front of the cross head 34 and to the rear of the same are collars 35, the construction being such that although the cutter shaft 20 may 20 rotate in the cross head 34, a reciprocation of the cross head 34 will produce a reciprocation of the cutter shaft and cause the latter to slide to and fro in the hub 19 of the pinion 18.

Secured to the shaft 30 are pinions 36 meshing into gear wheels 37 fixed to an auxiliary shaft 38 journaled in the bearings 11 and terminally supported in bearings 57 on the side portions of the casing 2, Fig. 7 being noted particularly for a disclosure of the details last above mentioned.

The gear wheels 37 are composite structures, each gear wheel comprising an intermediate disk 39 carrying a toothed rim 40 35 forming the operative element of each gear wheel 37. To the opposed faces of the intermediate disks 39 of the gear wheels 37 are applied side disks 41 and 42. The auxiliary shaft 38 is threaded as shown at 43 40 to receive nuts 44 which bear against the side disks 41. Keys 46 are provided, the same have enlarged heads 45, the keys 46 being received in seats 47 in the auxiliary shaft 38. The keys 46 engage in seats 48 in the 45 side disks 41, the enlarged heads 45 of the keys 46 being received in inclined seats 49 in the disks 42. The intermediate disks 39 are provided with central openings 50 of sufficient size, under conditions to be explained hereinafter, so that the disks 39 may 50 rotate independently of the disks 41 and 42 and independently of the keys 46. The heads 45 of the keys 46 co-operate with the disks 42 to hold the same against lateral 55 movement, but the disks 41 may be advanced against the disks 39 by rotating the nuts 44, the disks 42 acting as abutments for the disks 39. By the operation above described, the disks 39 may be connected with the shaft 60 60 38 with a varying frictional hold, to the end that, under excessive strains, the disks 39 may rotate independently of the shaft 38, thus avoiding a breakage of parts, it being understood, however, that by the action of the nuts 44 and the disks 41, the

disks 39 ordinarily are bound against the disks 42 with sufficient pressure so that a rotation of the disks 39 will produce a rotation of the shaft 38.

Mounted to rotate upon the shaft 38 adjacent the gear wheels 37 above described in detail are pinions 51, the outer ends of which are supplied with clutch elements 52. These clutch elements 52 are adapted to co-operate with the inner ends of clutches 53 75 held to the shaft 38 for rotation therewith but for sliding movement therealong, by means of keys 54, it being noted at this point, referring to Fig. 7, that the inner ends of the keys 54 serve as abutments for 80 the outer side faces of the pinions 51, so that the latter cannot move longitudinally of the shaft 38.

Journaled on the shaft 38 adjacent the ends thereof are pinions 55 having clutch elements 56 adapted to co-operate with the outer ends of the clutches 53, the pinions 55 lying adjacent the bearings 57.

The pinions 51 mesh into gear wheels 58 located upon the outer faces of drums 59 90 and 60 supported on a drum shaft 64, the latter being carried by the bearings 11 as Fig. 2 will disclose.

The outer faces of the drums 59 and 60 are provided with gear wheels 61 meshing 95 into idle pinions 62 journaled on stub shafts 63 carried by the side walls of the casing 2, the pinions 62 meshing into the pinions 55.

A flexible element 65 is trained around the drum 59 and engages with a guide sheave 100 66 on the supporting structure, the extremity of the flexible element 65 being carried laterally and being anchored to the side wall of the mine or elsewhere, as shown at 67. A flexible element 68 is trained around the 105 drum 60 in a direction opposite to that in which the flexible elements 65 is trained around the drum 59. The flexible element 68 is carried across angularly disposed guide sheaves 69 and 70 and is extended laterally, 110 the extremity of the flexible element 68 being attached to the wall of the mine or elsewhere by means of an anchor 71.

The forward end of the cutter shaft 20 carries a cutter 72 preferably of the spiral type and including a collar 73 constituting a means whereby the cutter 72 may be assembled with the cutter shaft. The line of abutment between the collar 73 and the end of the cutter shaft 20 is denoted by the number 74.

The driving trains will now be traced out.

A reciprocating movement is imparted to the cutter shaft 20 through the medium of a train embodying the following elements:—The motor 12, its armature shaft 14, the pinion 15, the gear wheel 16, the clutch 25, the pinion 18, the key balls 23 or their equivalents, and the cutter shaft 20.

A reciprocating movement is imparted to 130

the cutter shaft 20 by a train embodying the following elements:—The motor 12, the shaft 14, the pinion 15, the gear wheel 16, the clutch 25, the pinion 18, the pinions 27, 5 the longitudinal shafts 26, the worms 28, the worm wheels 29, the pitmen 31, the cross head 34, the collars 35, and the cutter shaft 20. Through the coöperation between the elements last above outlined, the cutter 10 shaft 20 is caused to reciprocate in the hub 19 of the pinion 18 while the cutter shaft is rotated by the pinion 18.

Presupposing that the worm wheels 29 are rotated as above mentioned, the drums 15 60 are rotated from the worm wheels by the following gear trains:—The worm wheels 29, the shaft 30, the pinions 36, the gear wheels 37, the shaft 38, the clutches 53, the pinions 51, the gear wheels 58, and the 20 drums 59 and 60.

By shifting the clutches 53, the drums 59 and 60 may be rotated in a direction opposite to that above described by the coöperation between the following elements: The 25 gear wheels 37, the shaft 38, the clutches 53, the pinions 55, the idlers 62, the gear wheels 61, and the drums 59 and 60.

If the clutches 53 are set in the intermediate positions shown in Fig. 7, that is, out 30 of engagement with the pinions 51 and 55, then the drums 59 and 60 may be rotated independently of their driving mechanisms, this operation being desirable at times, in order that the flexible elements 65 and 68 35 may be drawn freely off the drums. Each of the drums 59 and 60 may be rotated in opposite directions by shifting the clutch 53 so that it engages the pinion 55 or the pinion 51. The reversal in the direction of 40 rotation of the drum is brought about by reason of the interposition of the idle pinion 62 in one gear train. The gear wheel 61 is of smaller diameter than the gear wheel 58 and when the drum is driven 45 through the medium of the gear wheel 61, the speed of rotation of the drum is increased. The drums 59 and 60 are driven from the shaft 38 by separate gear trains, and, thus, should one of the drums or its 50 gear train become inoperative, the other drum may still be operated, thus preventing the machine from becoming entirely useless, so far as the operation of the machine depends upon the rotation of one drum.

55 One of the weakest points in a machine of this type is at the place where the cutter 72 is joined to cutter shaft 20. In the present machine, the line 74 of abutment between the cutter 72 and the shaft 20 always reciprocates within the contour of the longitudinal bearing 8. If the juncture indicated by the line 74 is, as in the present instance, always maintained within the bearing 8, the joint in question is reinforced 60 and strengthened so that in practice, a

breakage does not occur. At times, notably when the machine is being transported, it is desirable to stop the rotation of the cutter shaft 20. This operation may be brought about by disengaging the clutch 25 70 from the clutch elements 24 on the hubs 19 and 17 of the pinions 18 and 16 respectively. Then the pinion 16 may rotate upon the hub 19 of the pinion 18 without actuating the latter.

75 Since the flexible elements 65 and 68 are trained in opposite directions around the drums 59 and 60, the flexible element 68 will be paid out as the flexible element 65 is drawn in. The flexible element 65 is 80 employed for advancing the machine laterally to cause the cutter 72 to act upon the work, and the flexible element 68 is employed for preventing the rear end of the machine from swinging around, due to the 85 pressure of the cutter against the work. The drums 59 and 60 rotate at the same speed, and consequently, the rear end of the machine cannot travel laterally at a greater speed than the front end of the machine. 90 If it is desired to swing around the rear end of the machine, the drum 59 may be uncoupled by placing the corresponding clutch 53 in an intermediate position, the drum 60 being coupled up for rotation from 95 the shaft 38 by manipulating the clutch 53 which is individual to the drum 60. Under the circumstances above described, the clutch 53 of the drum 60 is coupled up with the corresponding pinion 55, the gear wheel 100 61 actuating the drum 60 through the medium of the idler 62. The drums 59 and 60 or either of them may be used to move the entire machine laterally before the cutting operation is begun.

105 The guide sheaves 66 are duplicated and the sheaves 69 and 70 are duplicated at opposite sides of the machine. Consequently, the machine may be changed from a right hand cutter into a left hand cutter by reversing the directions in which the elements 65 and 68 are wound about their respective drums, the element 65 being carried rearwardly and the element 68 being carried forwardly.

110 As hereinbefore outlined, the center disk 39 of the gear wheel 37, coöperating with the side disks 41 and 42 may be employed to effect a drive, or, under excessive strain, may be permitted to slip, thereby avoiding a 115 breakage of parts.

120 Having thus described the invention, what is claimed is:—

1. In a mining machine, inner and outer independently rotatable members, means for rotating the outer member; a clutch forming an operative connection between the rotatable members; a cutter shaft mounted for longitudinal reciprocation in the inner member; means for connecting the cutter shaft 125

and the inner member for simultaneous rotation; and mechanism operatively connecting the inner member with the cutter shaft for reciprocating the cutter shaft in the inner member.

2. In a mining machine, a supporting structure; inner and outer independently rotatable members; the cutter member being journaled in the supporting structure; means for rotating the outer member; a clutch forming an operative connection between the rotatable members; a cutter shaft mounted for longitudinal reciprocation in the inner member; means for connecting the cutter shaft and the inner member for simultaneous rotation; a second shaft journaled in the supporting structure and disposed substantially parallel to the cutter shaft; means for operatively connecting the second shaft with the inner member; and means for operatively connecting the second shaft with the cutter shaft to secure a reciprocation of the cutter shaft in the inner member.

3. In a device of the class described, a supporting structure; inner and outer independently rotatable members, the outer member being journaled in the supporting structure; means for rotating the outer member; a clutch forming an operative connection between the rotatable members; a cutter shaft mounted for longitudinal reciprocation in the inner member; means for connecting the cutter shaft and the inner member for simultaneous rotation; a second shaft journaled in the supporting structure and disposed substantially parallel to the cutter shaft; an operative connection between the second shaft and the inner member; a worm on the second shaft; a worm wheel journaled on the supporting structure, into which worm wheel the worm meshes; a cross head upon which the cutter shaft is rotatable; means for connecting the cross head and the cutter shaft for simultaneous reciprocation; and a pitman forming an operative connection between the worm wheel and the cross head.

4. In a mining machine, a supporting structure; inner and outer independently rotatable members; means for rotating the outer member; a clutch forming an operative connection between the rotatable members; a second shaft disposed substantially parallel to the cutter shaft and journaled in the supporting structure; intermeshing pinions, one of which is secured to the second shaft, the other of which constitutes a part of the inner rotatable member; and means for operatively connecting the second shaft with the cutter shaft to secure a reciprocation of the cutter shaft in the inner member.

5. In a device of the class described, a supporting structure; inner and outer inde-

pendently rotatable members, the outer member being journaled in the supporting structure; a clutch forming an operative connection between the rotatable members; means for rotating the outer member; a second shaft journaled in the supporting structure; a cutter shaft mounted for longitudinal reciprocation in the inner member; means for connecting the cutter shaft and the inner member for simultaneous rotation; a second shaft disposed substantially parallel to the cutter shaft; intermeshing pinions, one of which is mounted on the said second shaft, the other of which constitutes a part of the inner member; a third shaft journaled for rotation in the supporting structure and disposed transversely of the second shaft and the cutter shaft; a worm wheel on the third shaft; a worm on the second shaft and meshing into the worm wheel; a cross head in which the cutter shaft is rotatable; means for connecting the cross head to the cutter shaft for longitudinal reciprocation therewith; and a pitman forming an operative connection between the cross head and the worm wheel.

6. In a mining machine, a supporting structure; a rotatable member journaled therein; a cutter shaft mounted to reciprocate longitudinally in the rotatable member; means for operatively connecting the cutter shaft and the rotatable member for simultaneous rotation; a second shaft disposed substantially parallel to the cutter shaft; an operative connection between the second shaft and the rotatable member; a third shaft disposed transversely of the second shaft and the cutter shaft; a wheel on the third shaft; means on the second shaft for rotating the wheel; a cross head in which the cutter shaft is rotatable; means for uniting the cross head and the cutter shaft for simultaneous reciprocation; and a pitman forming an operative connection between the wheel and the cross head.

7. In a mining machine, a supporting structure embodying a bearing; a cutter shaft mounted to rotate in the bearing and to slide longitudinally in the bearing; a cutter on the cutter shaft; the line of union between the cutter and cutter shaft lying at all times within the contour of the bearing; and means for reciprocating the cutter shaft with the line of union between the cutter and the cutter shaft at all times within the contour of the bearing.

In testimony that I claim the foregoing as my own, I have hereto affixed my signature in the presence of two witnesses.
